UNITED STATES PATENT OFFICE.

FRANK MACMONNIES, OF NEW YORK, N. Y.

DESIGN FOR A BOTTLE.

SPECIFICATION forming part of Design No. 34,784, dated July 16, 1901.

Application filed June 14, 1901. Serial No. 64,595. Term of patent 14 years.

To all whom it may concern:

Be it known that I, FRANK MACMONNIES, a citizen of the United States, and a resident of New York city, county and State of New York, have invented a new and original Design for Bottles, of which the following is a specification, reference being had to the accompanying drawings, in which—

Figure 1 is a side elevation of my newly-designed bottle. Fig. 2 is a cross-section on line 2 2, Fig. 1; and Fig. 3 a bottom view of the bottle.

The leading feature of my design consists of a bottle having a body provided with five equidistant swells or corrugations *a*, jointed by the reentrant angles *b*. At the tops the swells merge into the flanged cylindrical neck *c*.

The cross-section of the bottle represents a five-pointed star with five rounded points. ²⁰ The bottom *d* is also five-pointed and is provided with an undulating flat rim *e*, from which the main portion of the bottom projects upward uniformly toward the center.

What I claim is—

The design for a bottle, substantially as herein shown and described.

Signed by me at New York city, county and State of New York, this 12th day of June, 1901.

FRANK MACMONNIES.

Witnesses:

F. V. BRIESEN,
WILLIAM SCHULZ.
